LABELING MACHINE

Sidney T. Carter, Shrewsbury, Mass., assignor to Geo. J. Meyer Manufacturing Co., Cudahy, Wis., a corporation of Wisconsin

Filed June 27, 1963, Ser. No. 291,140
18 Claims. (Cl. 156—566)

This invention pertains to labeling machines of the so-called "straight-away type" wherein articles to be labeled are advanced along a substantially rectilinear path by a conveyor and wherein, as the article to be labeled passes through a label-applying zone, a suction grip device takes a gummed label from a picker, located at one side of the article path, and presses the label into adhering contact with the moving article.

The invention relates more especially to a machine of the above general type, but wherein but a single article is labeled during each cycle of the machine and which is designed with special reference to saving in space.

Objects of the invention are to provide an improved labeling machine of the kind wherein articles, for example bottles, are moved uninterruptedly through a label-receiving zone; which is capable of applying one or a plurality of labels, including front, back, shoulder and neck labels simultaneously; which requires but little attention on the part of the operator; which provides precise label registration; which occupies relatively little floor space as compared with most high production machines, but which is capable of applying labels at a high production rate; to provide a labeling machine having provision for driving it at several different speeds; to provide a machine having automatic means responsive to the rate of supply of articles to the machine thereby to vary its speed and including manually-actuatable means whereby the machine may be shifted from one speed to another at will; to provide automatic means operative to prevent the delivery of labels from the magazine except when articles are approaching the labeling zone; to provide a labeling machine of the kind wherein the article to be labeled is firmly clamped by hold-down means against the conveyor while passing through the label-applying zone and wherein the hold-down means is vertically adjustable to accommodate articles of different heights; and comprising means for wiping neck labels which is vertically adjustable concomitantly with the adjustment of the hold-down means; to provide a machine of the above type which comprises article-orienting means operative, by engagement with a part of the article to be labeled, to turn the article approximately to the desired position of orientation; and having further means operative thereafter to turn the article to a final and accurate position of orientation and positively to grip and hold the article in the latter position while concomitantly holding the article so that its axis is accurately perpendicular to the conveyor just before the hold-down device, by contact with the top of the article, clamps the latter firmly to the conveyor.

Other objects and advantages of the invention will be pointed out in greater detail in the following description and by reference to the accompanying drawings wherein:

FIG. 1 is a small scale, diagrammatic front elevation illustrative of a machine embodying the present invention, but omitting many of its parts;

FIG. 2 is a diagrammatic end elevation of the machine of FIG. 1, viewed from the left-hand end of the machine;

FIG. 3 is a diagrammatic plan view showing the general location of certain essential parts, in particular, the article conveyor, the labeling station, the means for spacing the articles and for straightening them, and certain elements of the electrical system;

FIG. 4 is a view generally similar to FIG. 1, but to

2

larger scale, showing more particularly those parts which are located below the table of the machine, including the main shaft and the cams mounted thereon;

FIG. 4a is a fragmentary front elevation, to larger scale than FIG. 4, showing certain of the parts which are located above the table, in particular, the article spacer means, the article-straightening means and the labeling instrumentalities;

FIG. 4b is a fragmentary detail, illustrating one of the control switches;

FIG. 5 is a fragmentary diagrammatic section substantially on the line 5—5 of FIG. 4;

FIG. 5a is a fragmentary view showing the upper right-hand portion of FIG. 5, only, but with the parts there illustrated disposed in different relative positions;

FIG. 6 is a fragmentary section on the line 6—6 of FIG. 4, showing the cam for opening the picker;

FIG. 7 is a fragmentary section in the same plane as FIG. 5, showing, in detail, the cam for rocking the picker;

FIG. 8 is a fragmentary section on the line 8—8 of FIG. 4a, showing the cam and associated parts for moving the picker and wipers bodily in a longitudinal direction in consonance with the motion of the conveyor;

FIG. 9 is a fragmentary section on the line 9—9 of FIG. 4, showing the cam for actuating the gum transfer roll;

FIG. 9a is a fragmentary front elevation, showing the gum transfer roll and the means for supporting it;

FIG. 10 is a fragmentary section on the line 10—10 of FIG. 4a, showing the cam and the rocker devices for actuating the grip-finger assemblies;

FIG. 11 is a small scale front elevation showing one of the rock-shafts upon which the straightener, grip-finger and wiper, at one side of the machine, are mounted;

FIG. 12 is a fragmentary vertical section substantially on the line 12—12 of FIG. 4a, showing the bottle straightener device engaging a bottle;

FIG. 12a is a fragmentary, small scale, diagrammatic elevation showing the relation of the bottle-straightening device and the axis of rotation of the guide sprocket for the hold-down belt;

FIG. 13 is a fragmentary vertical section substantially on the line 13—13 of FIG. 4a;

FIG. 13a is an elevation showing the article-contacting face of one of the grip-fingers;

FIG. 14 is a fragmentary section on the line 14—14 of FIG. 4a;

FIG. 15 is a fragmentary section on the line 15—15 of FIG. 4a;

FIG. 16 is a plan view, showing certain of the parts illustrated in FIG. 12, as operatively related to a bottle (shown in broken lines);

FIG. 16a is a fragmentary edge view, to larger scale, of one of the bottle-contacting elements of the bottle straightener device;

FIG. 17 is a fragmentary plan view showing a suction grip-finger in operative position relatively to a bottle, the latter being indicated in broken lines;

FIG. 18 is a diagrammatic plan view, illustrating one of the wipers shown in FIG. 14, and indicating a bottle in broken lines;

FIG. 19 is a plan view illustrating one of the wipers shown in FIG. 15, and indicating a bottle in broken lines;

FIG. 20 is a fragmentary plan view, to larger scale, showing the star wheel for spacing the articles, the primary spotting means, and the secondary spotting and straightening means;

FIG. 21 is a fragmentary elevation of the parts shown in FIG. 20, viewed from the side opposite that at which the star wheel is located and showing, in section, a portion of the rock-shaft on which the wipers are mounted;

FIG. 22 is a fragmentary elevation showing parts of the spotting mechanism viewed from the side at which the star wheel is located;

FIG. 23 is a fragmentary elevation of the parts shown in FIG. 22, viewed from the right-hand side of the latter, showing the rock-shaft in section;

FIG. 24 is a fragmentary plan view showing a spotting dog arranged to engage a tear drop projecting from the bottle;

FIG. 25 is a view similar to FIG. 24, but showing a spotting dog arranged to cooperate with a depressed spotting bar Y¹;

FIG. 25a is a fragmentary horizontal section, to larger scale than FIG. 24, showing details of the spotting dog;

FIG. 26 is a fragmentary vertical section on the line 26—26 of FIG. 20 and in a plane perpendicular to the article path, showing the rack and pinion by means of which the bottle-spinning discs are turned;

FIG. 27 is a fragmentary vertical section showing the means for driving the endless chain on which the bottle-spinning discs are mounted;

FIG. 28 is a fragmentary plan view illustrating means for orienting the bottle to its final position;

FIG. 29 is a small scale, diagrammatic vertical section in substantially the same plane as FIG. 12, showing an orienting device, such as that of FIG. 28, as associated with means engageable with the bottle neck for straightening the bottle;

FIG. 30 is a fragmentary diagrammatic view looking from the left-hand side of FIG. 1, but to larger scale, showing automatic means for stopping the main shaft and certain switches comprised in the electrical system;

FIG. 31 is a fragmentary view at right angles to FIG. 30, showing the pneumatic cylinder whereby the speed of the main shaft may be varied;

FIG. 32 is a small scale vertical section substantially on the line 32—32 of FIG. 20, showing the connections below the table of the machine for driving the primary spotting means;

FIG. 33 is a section, to larger scale, in a plane perpendicular to that of FIG. 32;

FIG. 34 is a fragmentary diagrammatic elevation showing the lower part of a bottle and illustrative of the capability of the primary spotting means to cooperate with spotting elements of different types or differently located;

FIG. 35 is an elevation, to small scale, illustrating an attachment which may be mounted upon the support for holdown device so as to be vertically movable with the latter, said attachment comprising wiper brushes for wiping neck labels;

FIG. 36 is a plan view of the attachment shown in FIG. 35;

FIG. 37 is a section, to larger scale, on the line 37—37 of FIG. 35;

FIG. 38 is a section on the line 38—38 of FIG. 35;

FIG. 39 is a section on the line 39—39 of FIG. 35;

FIG. 40 is a fragmentary elevation showing the oil and vacuum pump;

FIG. 41 is a fragmentary elevation showing a portion of the control panel;

FIG. 42 is a fragmentary elevation illustrating certain of the parts within the control panel;

FIGS. 43 and 44 are diagrams illustrating the electrical wiring circuit of the machine; and

FIG. 45 is a time chart illustrating the relative positions of various parts of the machine during a single cycle of operation.

The machine in which the present invention is embodied is, in many respects, similar to the high-capacity machine disclosed in the patent to Carter, No. 2,940,630, dated June 14, 1960, to which reference may be made for details of construction not herein specifically illustrated or described. As in the patented machine, the operative elements are supported by a suitable frame F (FIG. 4) whose design is well within the province of the skilled

machine builder and which is not herein described except when referred to, incidentally, in describing individual parts of the operative structure. The frame includes a horizontal table T beneath which the motor M (FIGS. 1 and 31), main drive shaft 119 and most of the actuating cams are located. The drive shaft 119 turns through an angle of 360° for each cycle of operation, that is to say, during that sequence of motions of the essential label-applying devices which includes the application of glue to the picker; removal of a label or labels from a magazine by the picker; the transfer of the label from the picker to a single article by a suction grip-finger; the wiping of the label by a first wiper means; and the return of the picker to its initial position. However, the completion of the wiping by a second wiper means occurs during the succeeding cycle.

The machine is designed to receive articles to be labeled (herein referred to for convenience but not by way of limitation as "bottles") from a suitable supply and to deliver them, after the labels have been applied, to any desired type of receiver. Since the supply of articles, at times, may fail to provide articles as fast as the labeling machine can handle them, provision is made, in accordance with the present invention, for automatically varying the speed of the labeling machine to coordinate its operation with other machines with which it is associated. Provision is also made for the manual variation of the speed, and for automatically stopping the conveyor and label-applying instrumentalities in the event of accident.

As diagrammatically illustrated in FIG. 3, the machine comprises an endless conveyor C comprising a link chain 100 (FIG. 12), each link of which is provided with a flat plate, usually of steel, these plates, in the upper horizontal run of the conveyor, collectively providing a support on which the articles B rest as they are moved along the article or conveyor path, this type of conveyor being conventional in this art. For confining the articles and steadyng them as they move along the article path, appropriate guide rails 102 and 103 (FIGS. 1 and 4) are provided, with provision for adjusting them both horizontally and vertically, as is customary in apparatus of this type, to accommodate articles of different dimensions. At the left-hand end of the machine (FIG. 4), a horizontal shaft 104 carries a guide sprocket about which the chain 100 passes; while at the right-hand end of the machine the chain passes about a drive sprocket 105 mounted on a shaft 106 which is driven by a sprocket chain 160a passing about a sprocket on the output shaft of a speed-reducing mechanism 106x. The upper run of the chain rests upon support 100a (FIG. 12) of conventional type whereby said upper run is kept horizontal. The input shaft of the speed-reducing mechanism 106x is driven by suitable gearing (not shown) from the main shaft 119 and the latter shaft is driven by suitable speed-reducing mechanism R whose input shaft 20 is driven by the electric motor M (FIGS. 4 and 30), by means of an endless belt 22 (FIG. 31) which is variably tensioned by a pulley 25 whose position depends upon the pressure of air within a cylinder 29. A hand wheel W (FIG. 30) on the input shaft of the speed-reducer R permits the manual turning of the main shaft 119 when the motor M is de-energized thereby to facilitate the adjustment of parts of the machine. Means for controlling the admission of air to and its exhaust from the cylinder 29 will be described hereinafter.

The drive for shaft 20 (FIG. 30) is of the so-called "Reeves" type such that, by varying the tension of the belt 22, the speed of the shaft 20 may be varied. Such variation in the tension of the belt is accomplished by motion of the pulley 25 in response to the admission or release of air from the cylinder 29. Admission of air to this cylinder has the effect of decreasing the speed of the shaft 20.

The machine comprises a vacuum pump VP (FIG. 40) with associated drive motor M¹ and air-controlling valves

which may be, in general, like or the equivalent of the corresponding parts found in the patent to Carter above referred to. The machine also includes a lubricant pump LP (FIG. 40) of conventional type, together with means for controlling its operation which is designed to supply lubricant to the bearings of the machine when required.

It is customary in labeling machines to provide a hold-down device or "head grip" for applying downward pressure to the tops of the articles which are being labeled, in order to clamp the articles to the conveyor and thereby prevent them from tipping when subjected to the lateral thrust imposed in applying a label to the side of the article. Since, in the machine of the present invention, the articles are moving uninterruptedly along the article path while the labels are being applied, it is necessary that the hold-down means be of a character such that it may apply pressure to the articles while they are moving through the labeling zone. A hold-down device D (FIG. 1) of the endless belt type is embodied in the present machine. This hold-down device D may be of the type more fully described in the above patent to Carter, No. 2,940,630, but is preferably of the kind more specifically disclosed in the copending application of Sidney T. Carter, Ser. No. 252,638, filed January 31, 1963, since issued as Patent No. 3,215,255, dated Nov. 2, 1965, to which reference may be had for a more detailed disclosure. Since the hold-down device herein employed is adjustable vertically to accommodate articles of different heights, as disclosed, for example, in the above-noted patent, No. 2,940,630, and since, for properly wiping neck labels, it is desirable to employ rotary bush wipers, the present invention takes advantage of the provision for vertical adjustment of the frame of the hold-down device to employ said frame as a support for rotary brush wipers and to drive said rotary wipers by the same means which drives the endless belt of the hold-down device. These brush wipers and the means for supporting and driving them will be more fully described hereafter.

At the entrance end of the machine the articles which are being advanced by the conveyor C are engaged, as here shown, for example, by a rotating star wheel S (FIGS. 1, 2, 3, 4a and 20), located at one side (here referred to as the "rear side") of the article path. This star wheel is desirably of the kind more fully disclosed in the patent to Carter, No. 2,638,202, dated May 12, 1953, receiving its motion through suitable connections (not here shown) from the main shaft 119 and thus moving in accurately timed relation to the conveyor C. The star wheel, as thus disclosed in the last-named patent, is so devised that if the rotation of the star wheel be obstructed, it is automatically disconnected from its drive means thereby to avoid breakage of parts. The connections for driving the star wheel are so designed that the star wheel may be adjusted in or out to accommodate bottles of different sizes and the star wheel drive is such as to permit but one article to advance along the conveyor path for each complete revolution of the main shaft.

The general structure of the machine is such that, if desired, it may apply labels simultaneously to opposite sides of the same bottle as the bottle moves along the conveyor path and also to apply body, shoulder and neck labels. This involves the provision of a gumming station G (FIG. 3) at each side of the conveyor path and likewise means at each side of the article path for affixing and pressing or wiping the labels. The means for supplying gum, applying it to the labels and bringing the labels into adhering contact with the bottles may be, if desired, generally such as fully described and illustrated in the above patent to Carter, No. 2,940,630. Each gumming and labeling station thus includes a magazine or label-holder assembly (not here specifically illustrated), but which, for example, may be like the universal label holder more fully illustrated and described in the copending application for Letters Patent Ser. No. 214,952, filed 75

Aug. 6, 1952, by Sidney T. Carter, since issued as Patent No. 3,215,582, dated Nov. 2, 1965. Each gumming and labeling assembly will also include a gum box 194 (FIGS. 2, 3 and 4) with a constantly rotating gum-supply roll 195 which receives gum from the gum box; and an oscillatory gum-transfer roll 197, FIG. 9a (actuated by a cam 205, FIG. 9, on the main shaft), which takes gum from the roll 195 and applies it to a picker P (FIG. 1) of the separable-blade type. This picker comprises the relatively movable blades 174 and 174a (FIG. 1) and is mounted to oscillate about the axis of the picker shaft 175 (FIG. 5). The picker shaft is rocked by a cam C¹ (FIG. 7) on the main shaft 119 which, by yieldable, motion-transmitting connections, including the rod 182 (FIGS. 4, 5 and 7a) rocks a crank 175m (FIG. 5) secured to the picker shaft 175. A second cam C³ (FIGS. 4 and 6) on the main shaft 119, through suitable yieldable connections, including the rod 191 actuates a rocker device 189 (FIG. 4) by means of which the picker blades are moved toward and from each other at the proper times. To prevent the picker from taking labels from the magazine when there are no bottles positioned to receive labels, the machine is provided with means of known type including a solenoid SV-4 (FIGS. 4, 5 and 5a) which, so long as it is energized, permits the connections, above referred to, to rock the picker to take a label from the magazine at each cycle of operation, but when the solenoid is de-energized, the effective length of the motion-transmitting means, including the rod 182, which convey motion from the cam C¹ to the crank which rocks the picker, is shortened, as shown in FIG. 5a, so that the picker is not able to reach the magazine.

In the above-mentioned patent to Carter, No. 2,940,630, each of the grip-fingers at opposite sides, respectively, of the machine, which take labels from the pickers and transfer them to the articles which is to be labeled, as well as two wipers, are supported by the shaft which is arranged to rock and also to move endwise in suitable fixed bearings. These shafts are here indicated by the numeral 207 (FIGS. 4, 10 and 21) and are supported in bearings 208 (FIG. 4) mounted on adjustable plates resting on the table T of the machine.

A crankarm 218 (FIGS. 4a and 15), fixed to each respective shaft 207, is connected by resiliently yieldable links 219 to a rocker 220 pivotally supported at 221 to a fixed bracket 222. This rocker is connected by a link 223 of adjustable length to the free end of a rock-arm 224 pivotally supported by a bracket 225 beneath the table T. A cam follower roll 226, engaging a groove in a cam C⁴, fixed to the shaft 119, is operative to impart rocking motion to the two shafts 207, the arrangement being such that these shafts swing in opposite directions toward or from each other.

For moving these shafts axially, each shaft 207 is swivelled at one end to a link 210 (FIG. 4a) which, in turn, is pivotally connected to a transverse shaft 211 (FIGS. 4a and 8) journaled in the upper ends of upstanding parallel arms 212 (FIG. 8) of a rigid U-shaped rocker 212a which is mounted to rock on a shaft 212b supported by brackets 222 below the table T. This rocker also comprises the transverse member 222a rigidly connecting the arms 212. Parallel lugs 212a, integral with the member 222a, are provided with pintle members 220a pivotally supporting one end of a plate 223a (FIG. 4a), whose other end is pivotally connected to the lower end of a rock-arm 224a (FIG. 4a) pivotally supported by a bracket 225a (FIGS. 4a and 8) at the underside of the table T. A vertical pivot pin 223x, fixed to the plate 223a, supports a roll 226a which engages a peripheral cam groove in a cam C⁵ (FIG. 4a) fixed to the shaft 119.

The grip-finger assemblies at opposite sides of the machine are fixed to sleeves 207a (FIG. 4a), each mounted on one of the shafts 207 so as to move axially with the shaft but free to rock relatively to the shaft. For rocking the sleeve 207a, each sleeve is provided with a

7

crankarm 328 (FIGS. 4a and 10) which is rocked by yielding connections, including a rod 329, the lower end of which is pivotally connected to a rocker 330 mounted to rock at 331 on a bracket 332 fixed to the machine frame. A rod 333 of adjustable length connects the rocker 330 to a lever arm 334 (FIG. 10) pivoted at 335 to a bracket 336 below the table T. A cam roll 337, carried by the lever 334, engages a groove in a face cam C² on the shaft 119. By this means, oscillating motion is imparted to each sleeve 207a thereby to rock its grip-finger from the transfer position toward the article path and back again. The cam C² is so contoured that when the grip-finger first contacts the label, it slows down momentarily to permit the vacuum, at the suction orifices of the grip-finger, to build up to maximum before the grip-finger passes between the picker blades, thus to insure proper label registration and that the label will be gripped firmly by the grip-finger.

Each grip-finger assembly (FIGS. 13, 13a and 17) comprises a rigid arm 700 (FIG. 13) secured at its lower end to a corresponding rocker member 701 fixed to the sleeve 207a, which is rotatable relatively to the shaft 207 and movable axially together with the shaft. At its upper end, each of the arms 700 carries a housing 702 (FIG. 13) for a resilient pad 702a (FIG. 13a), having therein a suction passage 703 (FIG. 13) which terminates at a suction port 704 (FIG. 13a) in the face of the pad. Desirably, the face of each pad has a series of channels 705 communicating with the port 704. A conduit 706, at its upper end with the passage 703, extends downwardly along the arm 700, which may be interiorly of the arm but here shown as exteriorly of the arm, and is connected at its lower end to an axial bore 207m (FIG. 21) in the shaft 207 and thus, as hereafter described, communicates with a vacuum pump.

At its left-hand end each shaft 207 (FIG. 21) has a rigid tubular extension 600 (FIGS. 4a and 21) which is secured to the shaft 207 air-tight by a flexible connector 600a, for example one comprising a ball joint. Within this tubular extension 600 there is arranged to telescope a rigid tube 602, FIG. 21 (having an axial bore 602a) which is anchored at 603m (FIG. 4a) by a connector like the connector 600a, to a part 603a of the machine frame and whose inner bore communicates, through a passage in the frame, with a conduit extending to the vacuum pump VP. Between the non-reciprocating tube 602 and the extension 600, there is provided suitable packing 600x, for example, a so-called labyrinth packing, to prevent leakage as the shaft 207 and the extension 600 reciprocate. In this manner, the suction orifices of the grip-finger assembly are connected at all times to the vacuum pump without requiring the use of flexible tubing.

In accordance with the present invention, wiper means is provided for applying wiping pressure to each label in two stages first, a primary wiping by means of a thick, relatively soft pressure P^1 (FIGS. 4 and 18) and then, during the succeeding cycle, a final wipe by a suitably shaped presser P^2 (FIGS. 4a and 19) capable of imposing firmer pressure.

The primary wiper P^1 comprises a rigid arm 710 (FIGS. 4a, 14 and 18), secured at its lower end to a rocker 711 fixed to the corresponding shaft 207 , each arm 710 preferably having a series of openings 712 (FIG. 4a) to facilitate the adjustment of the wiper pad up or down to accommodate bottles of different heights. As shown in FIG. 18, the pad P^1 comprises a rigid base plate 713 which may be secured by a bolt or bolts to the arm 710 and having a mass 714 of soft resilient material, for example sponge rubber, plastic foam or the like, held within a flexible sheath 715 , for instance of soft leather, soft vulcanized rubber or textile fabric, with its edges attached to the plate 713 in any desired way, for instance by the use of a binding 716 of metal or the like, attached to the plate 713 by screws. Desirably, the pad P^1 , thus formed,

is so soft and resilient that when pressed against the peripheral surface of the bottle, a substantial part of the bottle, as indicated in broken lines in FIG. 18, will sink into the pad thus smoothing the label about the bottle, while expelling air from between the label and bottle and insuring the retention of the label in the proper position.

Each of the secondary wiper pads P² (FIGS. 4a, 15 and 19), comprises a rigid arm 720 attached at its lower end to a rocker 721 fixed to the shaft 207, and is desirably provided with a series of holes 722 (FIG. 4a) for the reception of bolts by means of which the pad holder may be adjustably secured to the arm 720. The pad comprises a rigid base 723 (FIG. 19) provided with spaced pivot pins 724, 725 on which are mounted rigid arcuate members 726 and 727 respectively, collectively forming a support for an arcuate pad 728, for example of vulcanized rubber, which is resiliently yieldable but substantially harder than the material of the pad P¹, the part 728, as here shown, being of an arcuate extent of the order of 120°. However, this is merely by way of example and its extent would be varied according to the width of the label to be applied.

The arms 710 and 720 which support the primary and secondary presser pads are spaced apart a distance such that when the pad P¹ is in operative engagement with a bottle, the pad P² will be in operative engagement with the bottle next in advance of that against which the pad P¹ is pressing a label. Thus, each label will be wiped or pressed into engagement with a bottle twice as it advances through the labeling zone, the successive wiping operations taking place at successive cycles of operation of the machine, respectively.

It is important that the bottles be accurately upright before being clamped in position by the hold-down device, but the action of usual spacing means, the vibration of the machine, and the slight irregularities common to usual bottles, tend to cause the bottles to lean slightly in one direction or another in approaching the hold-down device.

It has heretofore been proposed to provide bottle straightening means in association with the grip-finger but straightening means thus located may be too late in its action to accomplish the desired result. The present invention provides means operative to straighten the bottle in advance of the application of the label by the grip-finger and just before the bottle enters the field of action of the hold-down device. This straightening means may, in accordance with the invention, provide simply for applying force to opposite sides of the bottle in such a manner as to place the axis of the bottle in accurately vertical position and in the vertical plane of the center line of the conveyor path, or in a preferred embodiment the straightening means may comprise or be associated with means for accurately orienting a bottle having a spotting element, as well as for straightening it. For this purpose, and as shown in FIGS. 4a, 12 and 21 of the drawings, a rocker 605 is pivotally secured to the lower portion of a rigid upstanding arm 606 to which appropriate straightening means may be secured. To facilitate the application of straightening devices of different types or for use with bottles of different size, it is preferred to provide the arm 606 with a series of holes 607 adapted to receive screws, bolts or other fastening means for attaching the selected straightening element or elements.

As illustrated in FIG. 12, each of the shafts 207 is provided with a rocker 605 (FIG. 12) and corresponding arm 606, which are located at opposite sides of the conveyor path. Desirably, each arm 606 is pivotally connected to its rocker 605, with springs 606a (FIG. 12) so interposed between the arm and rocker as, while normally holding them in predetermined relation, permit the arm to yield in response to abnormal opposition to its movement toward the article path, which is the usual way, in this art, of connecting a grip-finger assembly to its rocker arm. To insure accurate positioning of the axis of the bottle in the vertical plane of the conveyor path, one of the arms

606, as shown in FIG. 12, is provided with an extension 606x which is engageable with an adjustable stop or abutment 606m which may be so adjusted as accurately to limit inward swing of the arm 606 toward the article path. Thus, although the arms are rocked toward each other by yieldable means, the final inward motion of one arm is positively determined.

Referring to FIGS. 16 and 16a, the arm 606, at the back side of the machine, is shown as having attached thereto a plate 606b to which, in turn, there is attached the vertical flange 607a of an angle member (FIG. 16a) whose horizontal flange 607m has a substantially rectilinear edge 608 parallel to the conveyor path. Desirably, this edge 608 is provided with a yieldable pad for contact with the bottle, for example a pad 630, as shown in FIG. 16a, comprising shoft resilient material, such as sponge rubber, embracing the edge 608, and held in place by a sheath 631, for example of soft leather or sheet plastic, secured to the flange 607m by bolts 632. As shown in FIG. 16, a plate 606b is also attached to the arm 606 which is at the front side of the machine, but to this plate there is secured an angle member whose horizontal flange 607a is cut away to form a recess 607b having edges 609 which converge toward each other at an angle of approximately 90°. These edges, like the edge 608 above referred to, are desirably provided with pads 631, such as above described, comprising soft material housed with a sheath of suitable material secured in place by bolts.

Alternatively, if the straightener be designed, not only to straighten the article but also as a secondary spotting device, then an arrangement such as that illustrated, for example, in FIG. 28 may be employed. In this arrangement, the arm 606 of the straightener member, at the front side of the machine (shown at the right-hand side of the view) is provided with an angle bracket 612, near its lower end (FIG. 29), said bracket having a horizontal flange upon which is pivoted a pair of angular, bottle-centering fingers 613 and 614, each finger comprising an arm 616, these arms being connected by a tension spring 617, and each having an arcuate, bottle-contacting edge 618, the spring 617 tending to swing these edges toward a bottle B disposed in the article path. The arm 606 at the opposite or rear side of the conveyor path has attached thereto, at its lower portion (FIG. 29) an angle member 612a having an approximately U-shaped horizontal flange 620 to which spotting fingers 621 and 622 are pivotally connected at 623 and 624 respectively. Each of these fingers 621 and 622 is provided with an outwardly directed arm 625 and these arms are connected by a tension spring 626, and each of these fingers is provided with a concave inner edge 627 and with a substantially rectilinear end surface or jaw 628 designed to engage a spotting element, for example a tear drop Y on the peripheral surface of the bottle B which is to be oriented. The arrangement thus illustrated in FIG. 28, is designed to perform a secondary or final spotting operation while, at the same time, straightening the bottle preparatory to its engagement by the hold-down device. Assuming that a bottle is advancing along the conveyor path and that the arms 606 of the centering device are swung upwardly and toward each other (while moving along the conveyor path with the bottle), and assuming that a preliminary orientation of the bottle has brought the spotting projection Y within a few degrees of that radius of the bottle which is perpendicular to the center line of the article path, the contact of the concave edges 618 of the fingers 613 and 614 with the surface of the bottle will tend to place and keep the axis of the bottle accurately positioned at the vertical center plane of the article path while at least one of the centering jaws 628 is in contact with the spotting projection or tear drop Y. As the arms 606 complete their movement toward each other, the action of the jaws 628 will be to turn the bottle slightly, if necessary, so as to bring the spotting projection Y exactly into a radial plane of the bottle which

is perpendicular to the article path. The bottle is thus held accurately oriented until the bottle is gripped by the hold-down device.

As illustrated in FIG. 29, each of the arms 606 also has a straightening element attached to it near its upper end, each such straightening element comprising an angle member 606x to whose horizontal flange there is bolted a horizontally adjustable plate 606c provided with a pad like that shown in FIG. 16a, for engagement with the bottle neck.

When the bottle has been finally and accurately oriented by the devices carried by the arms 606, it is immediately clamped down against the conveyor by the hold-down device D, FIG. 1, which, as above noted, is of the endless belt type, for example as disclosed in the copending application of Carter above referred to. As diagrammatically indicated in FIG. 12a, the arm 606 of the straightening device is so located, relatively to the axis of rotation of the guide sprocket H⁵ for the endless belt of the hold-down device D, that the axis of a bottle B, when held in vertical position by the hold-down device, is in the plane of rotation of said guide sprocket, that is to say, the bottle is thus straightened and held an instant before it is contacted by the downwardly moving part of the belt.

The hold-down device comprises a frame D² (FIG. 1) which is vertically adjustable to accommodate bottles of different heights. Since the machine may be called upon to apply neck labels, it is provided with an attachment 800 (FIG. 35), comprising a pair of spaced vertical brush shafts 801, 802, each having a brush B_x (FIG. 38) secured to its lower end. For convenience in turning these brushes and for adjusting the brushes up or down to accommodate bottles of different heights, the frame of this attachment is so designed that it may be secured to the frame D² of the hold-down device so as to partake of the vertical adjustment of the latter.

The hold-down belt, as described in said copending application, is driven by motion-transmitting connections from the main shaft of the machine, and among the motion-transmitting elements is a horizontal drive shaft upon which is fixed a sprocket wheel 804 (FIG. 37) which engages teeth on the hold-down belt so as to drive the latter in exact timed relation to the main shaft and conveyor. In accordance with the present invention, the brush attachment comprises an elongate rigid bar 803 (FIGS. 37, 38 and 39) which rests upon a horizontal flange of the frame D² and which is removably attached to the frame D² by bolts. Secured to this bar there are parts which provide bearings for the several shafts comprised in the mechanism (including the parallel, vertical shafts 801 and 802 on which the brushes are mounted) and a housing for the gearing.

Referring to FIG. 37, the numeral 804 designates the aforesaid sprocket for driving the hold-down belt and to this sprocket, in accordance with the present invention, there is bolted a spur gear 805 which drives a small gear 806 (FIGS. 35 and 37) mounted to turn freely on a horizontal stub shaft 807 fixed in a bore in the bar 803. The small gear 806 meshes with a gear 808 (FIGS. 35 and 38) which turns freely on a stub shaft 809 fixed in a bore in the bar 803. A bevel gear 810, integral with the pinion 808, meshes with a similar bevel gear 811 fixed to the brush shaft 801. The gear 808 also meshes with a spur gear 812 (FIGS. 35 and 39) which turns freely on a stub shaft 813 and which meshes with a similar spur gear 814 turning on a stub shaft 815. The spur gear 814 meshes with a gear 816 (FIG. 35) similar to the gear 808, which turns on a stub shaft 817 and which is integral with a bevel gear, similar to the bevel gear 811, which meshes with a bevel gear fixed to the brush shaft 802. Thus, the brush shafts are turned in opposite directions and at the same speed and are effective to wipe the opposite ends, respectively, of a neck label into adhering contact with the bottle neck.

As above noted, it is assumed that the bottle will have received a preliminary orientation before it reaches the field of action of the parts carried by the arms 606. A preliminary orienting or spotting means is illustrated in FIGS. 20 to 27 inclusive, and comprises a pair of endless chains 630 and 631 (FIG. 20) disposed, respectively, at opposite sides of the article path, the chain 630 being at that side at which the star wheel S is located. The chain 630 is trained about a sprocket wheel on a drive chain 632 (indicated in dotted lines in FIG. 20) and a shaft 632 (indicated in dotted lines in FIG. 20) and a guide sprocket on a stub shaft 633, while the chain 631, which is at the opposite or front side of the article path, is trained about a sprocket on a drive shaft 634 and about a guide sprocket on a stub shaft 635. The shafts 633 and 635 of the respective guide sprockets are carried by adjustable parts, such as the part 651, having spaced screw-threaded studs 652 engageable with a fixed part of a corresponding supporting frame 647 so that, by turning these studs, the shafts 633 and 635 may be adjusted toward or from the drive shafts 632 and 634, respectively, thus to place the chains 631 under proper tension. The sprocket on the drive shaft 634 is really a duplex sprocket (FIG. 27) comprising spaced upper and lower members 634a, the guide sprocket on the stub shaft 635 being of similar construction. The chain 631 (FIG. 26) is actually a duplex chain consisting of superposed like chains, each engaging one of the sprocket members 634a and being driven at the same speed. Certain registering links of the upper and lower members, respectively, of the duplex chain 631 (FIG. 26) are provided with aligned bearings for the reception of a shaft 640 upon which there is journaled a circular disc or roller 641 having attached thereto a spur pinion 642. A rack 643 (FIG. 26) is fixed to the frame 647 (which carries the shafts 634 and 635) in a position such as to be engaged by the teeth of the pinions 642 as the chain 631 moves the shafts 640 bodily along with that run of the chain which is moving in the same direction with the conveyor, the result being that each of the several rolls 641 will turn in a clockwise direction. The rolls 641 are arranged in pairs on the chain 631 to form what, for convenience, may be called "bottle-spinning couples," while the space between the proximate rolls of adjacent pairs of rolls is slightly in excess of the spacing between the two rolls constituting a spinning couple. Said pairs of rolls are so spaced apart, with relation to the design of the star wheel S, that each bottle, as it is delivered by the star wheel, will be interposed between the rolls of a spinning couple.

The chain 630, which is at the same side of the conveyor as the star wheel S, comprises four tiers of links with rolls 652 (FIG. 22) at intervals between the middle set of links, these rolls being suitably journaled on shafts carried by the links registering with the two inner chains. These rolls are spaced uniformly apart and there are as many rolls 652 carried by this chain as there are spinning couples carried by the chain 631. Associated with each of the rolls 652 is a two-armed dog 653 (FIGS. 24, 25 and 25a), provided with a spring 653x arranged to urge one arm of the dog toward the conveyor path, the dogs being so spaced along the chain that, as that run of the chain, which is adjacent to the conveyor path, moves along in time with the conveyor, the end of one arm 653a of the dog will contact the spotting projection Y on the bottle and thus terminate rotation of the bottle at a position such that the spotting projection Y is on a radius of the bottle which is approximately perpendicular to the conveyor path. The spotting dog 653 is capable of functioning either with a spotting projection or "tear drop" Y or with a spotting "bar" Y¹ forming a wall of a depression in the surface of the bottle. The spinning rolls 641, with their associate drive pinions 642, may readily be arranged so that the roll is either above or below the pinion, as illustrated in FIG. 34, in order to avoid, where necessary, interference between the drive

pinion for the spinning roll and the spotting element. The chains are so timed that as a bottle is released by the star wheel, it will be received between a pair of the rolls 641 (constituting a spinning couple) carried by the chain 631 and since these rolls are power-driven they will frictionally engage the periphery of the bottle and spin the latter about its vertical axis, the motion of the rolls 641, as shown in FIG. 20, being such as to tend to spin the bottle in a counterclockwise direction so that the spotting projection moves oppositely to the advancing dog 253 on the other chain. The roll 652, which is associated with each dog 653, contacts the peripheral surface of the bottle and thus positions the chain 630 so that the end of the dog will be accurately located to contact and stop rotary motion of the spotting projection Y as the dog meets the spotting element. The chains and their drive and guiding sprockets at opposite sides of the conveyor are carried by rockable supports 647 and the drive sprockets are driven by means of jointed shafts 636 and 637 (FIGS. 4a, 21, 22 and 23), which extend down through the table T where each is provided with a beveled gear 670, FIGS. 4a and 33 (only one being shown), said gears meshing, respectively, with beveled gears 671, FIG. 33 (only one of which is shown), fixed to parallel shafts 672 and 673 respectively (FIG. 32) to which spur gears 674 and 675 are fixed. The gear 674 meshes with a spur gear 676 while the gear 675 meshes with a spur gear 677. The gears 676 and 677 mesh with each other, and the gear 677 meshes with a spur gear 678 fixed to the main shaft 119, the gearing, as described, being such that the sprockets on the shafts 632 and 634 turn in opposite directions. Thus, those runs of the two chains 630 and 631, which are adjacent to the conveyor, move in the same direction as the conveyor, the gear ratios being such that the chains travel at exactly the same linear velocity as the conveyor.

Each support 647 (FIG. 20) is carried by a rigid U-shaped frame 680m (FIG. 22) fixed at its lower end to the machine frame, and having pivotally attached to its lower portion two pairs of parallel links 680 and 681a (FIG. 23), the upper ends of the links of each respective pair being connected to the support 647. The ends of a rigid rod 683 (FIG. 22) are fixed to the upper ends of the legs of the rigid frame 680m and provide anchorage for the upper ends of tension springs 684 whose lower ends are attached to a rigid rod 685, whose ends are fixed to the lower portions of the links 680, 681a. The springs 684 bias the supports 647 inwardly toward the conveyor so that the chains, at opposite sides of the conveyor path, are yieldably urged inwardly toward the conveyor path so as to insure the operative engagement of the bottle-spinning rolls and the spotting dogs with the bottles as the latter are advanced by the conveyor.

Electrical circuit and operation

Referring to FIG. 43, the numerals at the extreme left of the diagram designate the several circuits involved, in order to facilitate description. The circuits, numbered from 1 to 6 inclusive, are those of the main drive motor M and the drive motor M¹ for the vacuum pump VP, these motors being of conventional 3-phase type. Since customary symbols are employed in the diagram, it is believed unnecessary to describe each circuit in minute detail, but only to make reference to such parts as are necessary in explaining its function. As a preliminary to the description of the operation, the purpose of certain of the valves and solenoids is indicated in the following tables and description:

Limit switch functions

PH-1—Located between star wheel and straightener, detector or electric-eye (FIGS. 3, 43 and 44). Actuated by bottles entering the machine. Controls label-control solenoid SV-4 and speed of machine.

LSP-2—Located below speed-reducer R (FIG. 30). Sin-

gle pole-double throw, proximity switch. Actuated by cam on main shaft 119. Controls vacuum and air to grip-fingers.

LSP-3—Located below speed-reducer R (FIG. 30). Single pole-double throw, proximity switch. Actuated by cam on main shaft 119. Resets memory circuit once each cycle.

LSP-4—Located below speed-reducer R (FIG. 30). Single pole-double throw, proximity switch. Actuated by cam on main shaft 119. Controls label-control solenoid and speed of machine.

LS-5—Located on grip-finger up-and-down lever (FIG. 4a). Single pole-normally open. Maintained closed by a switch plate. Released when jam occurs in grip-finger.

LS-6—Located on wiper up-and-down lever (FIG. 4a). Single pole-normally open. Maintained closed by a switch plate. Released when jam occurs in wipers.

LS-7—Located on leg above speed-reducer (FIG. 30). Single pole-normally closed. Actuated by speed-reducer when jam or excessive loads occur in machine.

Solenoid functions

SV-1—3-way solenoid valve. Located under control panel. Controls air to speed-control cylinder 29.

SV-2—3-way solenoid pilot-operated valve. Located on back of control panel. Controls air and vacuum to grip-fingers.

SV-3—3-way solenoid valve. Located under control panel. Controls air to automatic lubrication pump.

SV-4—Label-control solenoids (FIG. 3). Located on side frame of each label station. Controls label-picking mechanism.

Operation

Provision is made for supplying compressed air to the machine from any suitable source (not here illustrated). Before the machine is started, an inlet control valve of conventional type (not shown) is opened manually to supply air to the speed-changing cylinder 29 in order that the machine may not start at maximum speed. In starting the machine, the "start button" (FIG. 41), located on the control panel, is pressed and thus starts both the drive motor M and the vacuum pump motor M¹. Assuming that no bottles are being fed to the machine, the machine will start at low speed and at this time the solenoid SV-4 (FIG. 5) will be de-energized so that the pickers will not take labels from the magazines. At this time, the 3-way vacuum solenoid valve SV-2 (FIG. 43) is being operated by the cam-actuated switch LSP-2 (FIG. 43) so that the grip-fingers will be receiving vacuum and compressed air alternately. As bottles are fed into the machine and are released, one-per-cycle by the star wheel S (FIG. 20), each advancing bottle will break the electric-eye beam at the scanning device PH-1 (FIGS. 3, 43 and 44) and will complete a memory circuit which controls the SV-4 label picker solenoids (FIG. 5). As the bottle passes the PH-1 scanning device, the memory circuit will energize the label-control solenoids SV-4 before the first bottle reaches the labeling station. The scanning device PH-1 also controls the speed of the machine. If the light beam is continually broken by bottles (once during each successive cycle), the SV-4 solenoid (FIG. 3) remains energized, the SV-1 solenoid valve (FIG. 43) will release air from the speed-control cylinder 29 and the machine will shift to and remain at high speed. However, when there occurs a space in the line of bottles so that the scanning device is not actuated during any one cycle, the valve SV-1 will admit compressed air to the control system 29 and cause the machine to drop to low speed until the flow of bottles is resumed. However, when the bottles first start passing the scanning device, the labeler will not go into high speed until after the label-control solenoid SV-4 is energized.

There is a "stop" push button on the panel Q, FIG. 41 (and at other points on the machine desired), so connected

into the control circuit that when any stop button is pressed while the machine is running, the drive motor and vacuum pump motor will immediately stop. Another control button, here referred to for convenience as the "inch" button is so connected into the circuit that when this button is depressed the drive motor will start but will stop instantly when the button is released, the vacuum pump motor will also start but will continue to run after the "inch" button is released. By this means the machine may be caused to operate for very short intervals, for example, for observation of its operation or for making minor adjustments.

There is on the control panel (FIG. 41) another button which controls the lubrication pump. Pressure on this button causes the lubrication pump LP (FIG. 43) to make one stroke and then immediately to stop. However, the machine also has a time clock TC (FIGS. 43 and 44) within the control panel Q which automatically closes the lubrication pump circuit so as to perform one cycle at regular intervals of time.

There is also a "wash-run switch" on the control panel (FIG. 41). Normally, this switch is in the "run" position and the machine will be running at normal speed but when the switch is shifted to "wash" position, the vacuum pump is de-energized; air will be continually blown through the grip-finger ports; the label-control solenoid SV-4 will be energized and the SV-1 solenoid will be de-energized so that the labeler will be running at low speed. This latter valve has already been referred to as controlling the flow of air under pressure to the speed-varying cylinder 29. When this valve allows air under pressure to enter the cylinder, the labeler runs at low speed but when it cuts off the supply of air from the cylinder, the labeler runs at high speed. The SV-2 solenoid valve is controlled by the cam-actuated switch LSP-2 (FIG. 30) and alternately supplies vacuum and air to the grip-fingers.

The solenoid valve SV-3 (FIG. 43) is a 3-way valve and is controlled by the time clock TC, or alternatively by the lubricant test button (FIG. 41) on the panel. When this valve is energized, it supplies air to the lubrication pump (LP) which supplies grease to the various grease fittings of the machine. The SV-4 solenoid (FIG. 5), as above pointed out, controls the taking of labels from the magazine by the picker and when energized allows the picker to function normally. The PH-1 scanning device responds to the passage of bottles advancing toward the labeling station and, by its response, energizes the memory circuit and likewise determines the speed of the machine. The LSP-2 switch (FIG. 30) is a cam-operated switch and controls the delivery of vacuum or air to the grip-fingers. The LSP-3 switch is a cam-operated switch (FIG. 30) and is included in the memory circuit. The LSP-4 switch (FIG. 30) is a cam-operated switch and, in cooperation with the memory circuit, determines the point in the cycle at which the label-control solenoid SV-4 (FIG. 5) is energized or de-energized. The switch LS-5 (FIG. 4a) is so associated with the means for actuating the grip-finger that, if the normal motion of the grip-finger is obstructed, this switch operates to cut the circuit of the drive motor and vacuum pump, this circuit being in series with the stop push button on panel Q. The LS-6 switch (FIG. 4a) is associated with the means for actuating the wipers and in the event of obstruction to the normal movement of the wipers, acts to stop the drive motor and the vacuum pump, this switch also being in series with the stop push button on panel Q. The LS-7 switch (FIG. 30) is associated with the mechanism for driving the main shaft of the machine and in the event that a jam occurs, such as to require excess torque for driving the shaft, this switch automatically breaks the motor circuit and stops the machine, this switch also being in series with the stop button on panel Q.

The location of the control panel Q upon which the

controls for the electrical system are mounted is shown in FIG. 1, and the location of certain of the switches, as well as that of the photoelectric detector device, are diagrammatically indicated in FIG. 3, while other switches are shown in FIGS. 4a and 5.

The following more specific description of the electrical circuit is combined with a description of the general mode of operation of the machine.

Electrical circuit description (FIGS. 43 and 44)

Circuit 8.—This circuit includes the grip-finger jam switch LS-5, the wiper excess pressure switch LS-6, the excessive torque switch LS-7 and the two "STOP" push buttons. All of these switches are connected in series and are closed during normal operations. Upon the opening of any one of these switches or push button contacts, the power to all the controls, except the electric-eye chassis, is interrupted, causing the motor starters DM and VM (circuits 16, 20), to de-energize and stop the drive and vacuum pump motors.

Circuits 10 and 11.—These circuits contain the time clock TC contacts, the grease test push button and the grease pump solenoid valve SV-3. The SV-3 solenoid valve, when energized, supplies air to the air-operated grease pump LP. The single stroke grease pump will remain in the single cycle position as long as the valve is energized. The valve is controlled by the time clock contact TC (12, 33) and the grease test push button on the panel Q (FIG. 41). When the TC contacts are closed by the time clock (circuit 21), the circuit through SV-3 valve coil will be completed when either the DM contacts (6, 12), (circuit 20), or the VM contacts (6, 12), (circuit 21) close so that the grease pump can only operate when either or both the drive motor or vacuum pump are running. Pressing the grease test push button will open its contacts (33, 34), (circuit 10), and close its contacts (6, 34), (circuit 11). This will bypass the time clock contacts TC (12, 33) and operate the SV-3 solenoid directly. This button is used to test the grease pump and to obtain an additional grease shot to the greasing system if needed.

Circuits 12 to 16.—Pressing the "START" push button will energize the magnetic starter DM. The closing of the push button contacts (6, 7) will energize relay CR-1 (circuit 12), and the closing of contacts (6, 8), (circuit 14) will energize the starter coil DM (circuit 16). The CR-1 relay contacts (6, 7), (circuit 10), will close, bypassing the push button contacts and lock in the CR-1 relay. The CR-1 contacts (6, 9), (circuit 16), will also close, and in conjunction with DM contacts (9, 8) will bypass the push button contacts (6, 8), (circuit 14), and lock in the starter coil DM, so that when the "START" push button is released, the drive motor will continue to run.

Pressing the "STOP" push button will de-energize CR-1 relay and DM starter, stopping the drive motor.

Circuit 18.—The pressing of the "INCH" push button will energize the CM starter coil and its drive motor will continue to run as long as the push button is held depressed. When the "INCH" push button is released, the DM starter will de-energize stopping the drive motor. The starter will not lock in as the CR-1 contacts (6, 9), (circuit 16), will not close.

Circuits 20 and 21.—This is the vacuum pump circuit. When the drive motor starts (circuit 16), the contacts DM (6, 12), (circuit 20) will close, energizing the VM starter coil starting the vacuum pump M¹. Upon energizing the VM starter, its contacts VM (6, 12), (circuit 21) will close, bypassing the DM contacts (6, 12) and locking itself in so that if the DM starter is de-energized, in the case where the "INCH" push button is used, the vacuum pump will continue to run until a "STOP" push button is depressed. The time clock TC in circuit 21 will run when either of the two contacts DM (6, 12) or VM (6, 12) are closed in circuits 20 or 21.

Circuits 22 and 23.—A cam-operated switch LSP-2 controls the operation of the SV-2 solenoid valve. The SV-2 valve in circuit 23 will only operate when the vacuum pump is running, and the VM contacts (16, 17) are closed. The LSL-2 pilot light (circuit 18) is used to check the timing of the LSP-2 cam-operated switch (circuit 22).

Circuits 24 to 28.—These circuits are the memory circuits which control the label-control solenoids SV-4 (FIG. 5) in circuits 29 and 30 through the CR-3 contacts (6, 23) in circuit 30. When the electric-eye light beam is not broken, that is, when there are no bottles passing by the scanner (photoelectric detector) or between the star wheel S and straighteners 606, the PH-1 contacts (6, 18) and (6, 24) in circuits 24 and 25 will be opened. LSP-3 cam-operated switch (circuit 27) will have no effect on relay CR-3 (circuit 25), which will remain de-energized. Under these conditions the SV-4 label control solenoid will not energize and no labels will be picked. The LSP-3 cam-operated switch is timed to close momentarily its contacts (19, 36) once each cycle, at the same time that a bottle is interrupting the electric-eye beam after being released by the star wheel. The remaining part of the cycle, the LSP-3 switch contacts (19, 36) are opened and its contacts (19, 20) are closed. When a bottle enters the labeler and interrupts the light beam, the LSP-3 switch contacts (19, 36) close momentarily and complete the circuit to the CR-3 relay. The CR-3 relay energizes and closes contacts (36, 19) and (6, 20) locking in the CR-3 relay. When the bottle has advanced past the light beam, PH-1 contacts (6, 36) and (6, 18) will open. The CR-3 relay will remain energized, remembering that the bottle has passed the light beam and is entering the label station. The CR-3 relay contacts (6, 23), (circuit 30) also close and will cause SV-4 label-control to operate and label the bottle as it passes through the labeling station (see circuits 29 to 32). The CR-3 relay will remain energized until the next cycle when the cam-operated switch LSP-3 again opens its contacts (19, 20) and closes contacts (19, 36). If there is another bottle breaking the PH-1 electric-eye light beam at this time CR-3 relay will remain energized for another cycle. If there are no bottles interrupting the light beam, CR-3 will de-energize and open its contacts. In circuit 27, there is the SV-1 solenoid valve which controls the air to the speed control cylinder 29. When the CR-3 relay is energized in circuit 25 and the CR-2 contacts (25, 26) and CR-1 contacts (26, 27) in circuit 27 are closed, the SV-1 solenoid valve will energize and release the air from the speed control cylinder 29, allowing the drive to go into high speed. In order to run the labeler in high speed, three conditions must exist. First, the drive motor must be running so that CR-1 relay is energized; secondly, the label-control mechanism solenoids and the CR-2 relay must be energized, so that the labels are being picked; and thirdly, the memory control circuit must be actuated so that CR-3 relay is energized.

Circuits 29 and 30.—These are the label-control circuits. Once each cycle, the LSP-4 cam-operated switch will close its contacts (22, 23) and open its contacts (21, 22), (circuit 29) for a short period and the remainder of the cycle it will have its contacts (21, 22) closed and its contacts (22, 23) open. If when it closes its contacts (22, 23) the CR-3 contacts (6, 23), (circuit 30) are open, nothing happens and the SV-4 solenoid and CR-2 relay in circuits 29 to 31 remain de-energized. When CR-3 contacts (6, 23) are closed due to a bottle passing the electric-eye and actuating the memory circuit, the SV-4 solenoids and CR-2 relay will energize when the cam-operated switch LSP-4 closes its contacts (22, 23). When the LSP-4 switch opens the (22, 23) contacts and closes the (21, 22) contacts, the SV-4 solenoid and CR-2 relay will remain energized, even though the CR-3 contacts (6, 23) are opened, until the next cycle or time that the

LSP-4 switch is actuated again by its cam and opens the (21, 22) contacts.

Circuit 34.—This is the electric-eye chassis with scanner and light source. When the scanner sees the light beam from the light source, the electric-eye relay PH-1 contacts (6, 18) and (6, 36) will open. When a bottle breaks the light beam the PH-1 contacts close.

Circuit 30—“run-wash” selector switch.—When this switch is turned to the “wash” position, the following changes in the circuitry take place.

Circuit 20.—The contacts (12, 13) are opened. This prevents the vacuum pump from starting when the “start” push button is depressed. The vacuum pump is not used in the “wash” cycle.

Circuit 27.—The contacts (19, 25) are opened. This prevents SV-1 solenoid from energizing and keeps the labeler in low speed.

Circuit 32.—The contacts (6, 23) are closed, keeping the CR-2 relay and SV-4 label-control solenoids energized.

The neon pilot lights (FIG. 42) are used to check the timing and operation of the electric-eye and cam-operated proximity switches. The LSL-2 pilot light (circuit 18) is used to check the LSP-2 switch (circuit 22). The LSL-1 pilot light (circuit 24) checks out the PH-1 electric-eye (circuits 24 and 25). The LSL-3 pilot light (circuit 28) checks out the switch LSP-3 (circuit 27) and the pilot light LSL-4 (circuit 31) is used to check out LSP-4 switch in circuit 29. Each switch pilot light must be “on” for a given duration of time as indicated on a dial attached to the front end of the speed-reducer.

“Push to test” push button.—If this push button is held depressed when a bottle is entering the machine, the label control solenoid will not energize and the bottle will not be labeled. The purpose of the switch is to check the timing of the four pilot lights with reference to each other to see that the cam-operated switches and the electric-eye are operating in proper timing and sequence.

In FIG. 42, the electric-eye amplifier tube is indicated at 900; the electric-eye plug-in relay at 901; the time-delay adjusting screw for the electric eye at 902; the electric-eye sensitivity adjusting screw at 903; and the push button for closing the test-light circuit at 904.

FIG. 45 is a timing chart illustrating the sequence of events in the labeling cycle and is believed to be self-explanatory.

While one desirable embodiment of the invention has herein been illustrated and described by way of example, together with various suggested modifications, it is to be understood that the invention is broadly inclusive of any and all modifications which fall within the terms of the appended claims.

I claim:

1. A labeling machine of the kind wherein bottles to be labeled are advanced uninterruptedly by a conveyor along a substantially rectilinear path into and through a label-receiving zone, and wherein, while the bottle is passing through the label-receiving zone, it is prevented from turning by a hold-down device of the endless band type, and wherein spacer means, acting in exact time, relatively to the motion of the conveyor, disposes bottles in uniformly spaced relation as they approach the label-receiving zone, and wherein a grip-finger, within the label-receiving zone, is operative to take a label from a picker and apply it to the bottle; presser means within the label-receiving zone for pressing the label into firm adhering contact with the bottle, and primary and secondary spotting means operative accurately to orient the bottle just before it is engaged by the hold-down device, characterized in that the primary spotting means comprises endless chains disposed at opposite sides, respectively, of the conveyor path, each of said chains having a run which is parallel to the conveyor path, means for so driving said chains that said runs move in the same direction and at the same linear speed as the conveyor, one of said

chains supporting a series of spaced, independently rotatable bottle-contacting rolls, and means for turning said rolls while in contact with the periphery of the bottle thereby to turn the bottle about its own axis, as the bottle is advanced by the conveyor, and the other chain having spaced elements operative, by engagement with a spotting element forming a part of the bottle, to terminate rotation of the bottle while permitting the bottle to continue to advance through the label-receiving zone.

2. In combination, in a labeling machine of the kind wherein bottles to be labeled are advanced uninterruptedly by a conveyor along a substantially rectilinear path into and through a label-receiving zone, and wherein, while the bottle is passing through the label-receiving zone, it is prevented from turning by a hold-down device of the endless band type, and wherein spacer means, acting in exact time, relatively to the motion of the conveyor, disposes bottles in uniformly spaced relation as they approach the label-receiving zone, and wherein a grip-finger, within the label-receiving zone, is operative to take a label from a picker and apply it to the bottle; presser means within the label-receiving zone for pressing the label into firm adhering contact with the bottle, and primary and secondary spotting means operative accurately to orient the bottle just before it is engaged by the hold-down device, characterized in that said spotting means is located between the spacer means and the field of action of the grip-finger.

3. Labeling apparatus of the kind which includes means for driving a main shaft and wherein bottles, each provided with a spotting element, are moved along a predetermined path through a labeling zone by a conveyor, and having means for transmitting motion from the main shaft to the conveyor, and wherein a spacer device, arranged at one side of the conveyor path, is driven in accurately timed relation to the motion of the conveyor thereby allowing one bottle per cycle to advance into the labeling zone, and wherein a hold-down device engages the top of the bottle just before the bottle enters the labeling zone, and wherein in a grip-finger, within the labeling zone is operative to take a label from a picker and apply it to a bottle, characterized in having means interposed between the spacer device and the field of action of the grip-finger for orienting a bottle about its vertical axis, and straightening means interposed between the orienting means and the grip-finger for disposing said axis of the bottle in the vertical plane of the center line of the conveyor path.

4. In combination, in a labeling apparatus of the kind wherein bottles, each provided with a spotting element, are advanced by a conveyor along a predetermined path and through a labeling zone, and wherein a spacer device, arranged at one side of the conveyor path, is driven in accurately timed relation to the conveyor thereby to allow one bottle per labeling cycle to advance into the labeling zone, and means for orienting a bottle about its vertical axis as it approaches the labeling zone, characterized in that the means for orienting the bottle comprises endless chains, disposed at opposite sides, respectively, of the conveyor path, means for driving each chain at the same speed as the conveyor, means carried by one chain for spinning the bottle about its vertical axis, and means carried by the other chain, cooperable with a spotting element on the bottle, for terminating the rotation of the bottle.

5. In combination, in a labeling apparatus of the kind wherein bottles, each provided with a spotting element, are advanced by a conveyor along a predetermined path and through a labeling zone, and wherein a spacer device, arranged at one side of the conveyor path, is driven in accurately timed relation to the conveyor thereby to allow one bottle per labeling cycle to advance into the labeling zone, and means for orienting a bottle about its vertical axis as it approaches the labeling zone, characterized in that the means for orienting the bottle comprises an endless chain located at the opposite side of the article path

from the spacer device, said chain having a run which is parallel to and adjacent to the article path, said chain carrying a plurality of bottle-spinning rolls, each rotatable about a vertical axis, a support for the chain which is movable toward and from the article path, means for moving that run of the chain, which is adjacent to the article path, in the same direction as the conveyor, and means for turning the several spinning rolls in a direction such that that part of the peripheral surface of the bottle, which is adjacent to the other side of the conveyor path, moves oppositely to the conveyor.

6. In combination, in a labeling apparatus of the kind wherein bottles, each provided with a spotting element, are advanced by a conveyor along a predetermined path and through a labeling zone, and wherein a spacer device, arranged at one side of the conveyor path, is driven in accurately timed relation to the conveyor thereby to allow one bottle per labeling cycle to advance into the labeling zone, and means for orienting a bottle about its vertical axis as it approaches the labeling zone, characterized in that the spinning rolls are arranged in pairs upon the chain, the rolls of each pair being so spaced apart as to receive a portion of the periphery of a bottle between them and to make a tangential contact with the bottle at points spaced apart about its peripheral surface, and means for driving the chain at the same linear velocity as the conveyor.

7. In combination, in a labeling apparatus of the kind wherein bottles, each provided with a spotting element, are advanced by a conveyor along a predetermined path and through a labeling zone, and wherein a spacer device, arranged at one side of the conveyor path, is driven in accurately timed relation to the conveyor thereby to allow one bottle per labeling cycle to advance into the labeling zone, and means for orienting a bottle about its vertical axis as it approaches the labeling zone, characterized in that the means for rotating the spinning rolls comprises a rack parallel to the conveyor path and located beneath that run of the chain which is adjacent to the conveyor path, each spinning roll being fixed to a rotary shaft turning in bearings in the chain links, and a pinion fixed to each of said shafts arranged to engage the teeth of said rack.

8. In combination, in a labeling apparatus of the kind wherein bottles, each provided with a spotting element, are advanced by a conveyor along a predetermined path and through a labeling zone, and wherein a spacer device, arranged at one side of the conveyor path, is driven in accurately timed relation to the conveyor thereby to allow one bottle per labeling cycle to advance into the labeling zone, and means for orienting a bottle about its vertical axis as it approaches the labeling zone, characterized in that the support for the endless chain is mounted to swing about a horizontal axis parallel to the conveyor and located at one side of the latter and below the horizontal plane of the conveyor, and spring means tending to swing said support about said axis thereby to force the spinning rolls into contact with a bottle carried by the conveyor.

9. The combination according to claim 5, wherein the chain which carries the bottle-spinning rolls passes about drive and guide sprockets mounted upon vertical shafts having bearings in said support, motion-transmitting means operative to transmit motion from the main shaft of the machine to the drive sprocket for said chain, and means for adjustably positioning the shaft for the guide sprocket thereby properly to tension the chain which carries the spinning rolls.

10. The combination according to claim 5, wherein an endless chain, at the same side of the conveyor path as the spacer device, carries dogs at spaced intervals, each operative, by contact with the spotting element of a bottle, to terminate rotation of the bottle at a time when the spotting element is located on a radius of the bottle which is

approximately perpendicular to the center line of the conveyor path.

11. The combination according to claim 10, wherein each of the dogs is pivotally attached to the chain, each dog comprising an arm whose free end is engageable with the spotting element of the bottle, spring means tending to hold the dog in position such that the end of said arm will engage the spotting element of a bottle and thereby terminate rotation of the latter about its own axis, and means operative, by contact with the bottle, to position the dog for contact with the spotting element.

12. The combination according to claim 11, wherein each dog is a rigid two-arm pawl pivoted to a link of the chain, one arm having an end surface designed to engage a spotting projection on the peripheral surface of the bottle, and a freely rotatable roll, carried by the chain, just in advance of the dog and which, by contact with the bottle, positions the dog so as to engage the spotting element.

13. The combination according to claim 12, wherein each dog for stopping the rotation of the bottle comprises an arm having an end shaped for cooperation with a spotting element consisting of one wall of a cavity in the peripheral surface of the bottle.

14. The combination according to claim 3, further characterized in that the orienting means comprises primary means including devices located at opposite sides, respectively, of the article path for spinning the bottle about its vertical axis and for terminating its rotation, respectively, thereby to dispose the spotting element at approximately the desired position of orientation, and secondary orienting means operative to dispose the spotting element accurately on a radius of the bottle which is perpendicular to the center line of the article path, said secondary spotting means being associated with and operating in timed relation to the straightening means.

15. The combination according to claim 14, further characterized in that the secondary spotting means is located between the primary spotting means and the point at which the hold-down device contacts the tops of bottles, said secondary spotting means comprising two levers located at opposite sides of the article path, respectively, and pivoted to rock about axes parallel to the article path and below the horizontal plane of the conveyor, and means for rocking said levers toward and from each other, a bottle-straightening pad being mounted upon the free end of each of the respective lever arms and which is engageable with the neck of the bottle to straighten the latter, bottle-centering means mounted upon one of said arms and so positioned as to engage the periphery of the bottle in a plane adjacent to the bottom of the bottle, and the other of said lever arms carrying a pair of jaws operative, by engagement with the spotting element of the bottle, to locate said spotting element on a radius of the bottle which is accurately perpendicular to the conveyor path.

16. The combination according to claim 14, wherein the hold-down device comprises an endless band which passes about a drive sprocket and a guide sprocket, said sprockets providing a horizontal lower run of the band for engagement with the bottle top, and the secondary spotting means is arranged in the vertical plane of the axis of the guide sprocket and is operative to position the spotting element of the bottle accurately in said vertical plane.

17. A labeling machine of the kind which comprises conveyor means for moving articles to be labeled along a predetermined path, and means for applying labels to the articles while they are in said path, motor means, means for transmitting motion from the motor means to the conveyor means, a hold-down device of the endless belt type, a supporting frame for the belt, said frame being vertically adjustable to accommodate articles of different heights, means for transmitting motion from the motor means to said belt in all positions of adjustment of the frame, and a pair of rotary wiper brushes supported by

said frame and which are movable with the latter, and means for transmitting motion from the motor means to said brushes, characterized in that the brushes are mounted upon shafts having bearings in an auxiliary frame, means for removably securing said auxiliary frame to the frame which supports the endless belt of the hold-down means, said auxiliary frame housing a gear train operative to turn the brushes in opposite directions, and means for driving said gear chain in timed relation to the motion of the hold-down belt.

18. In combination, in a labeling machine of the kind wherein bottles to be labeled are advanced uninterruptedly by a conveyor along a substantially rectilinear path into and through a label-receiving zone, and wherein a suction-type grip-finger, located within the label-receiving zone, is operative to take a label from a picker and affix it to the advancing bottle, and wherein the grip-finger is mounted upon an axially movable rock-shaft, characterized in that said shaft has an axial bore open at one end of the shaft and which communicates with a suction port in the grip-finger, a tubular extension, one end of which is attached to the rock-shaft and whose interior communicates with the axial bore in the latter, a hollow piston which slides leak-tight within said tubular exten-
